[57] **CLAIM**

The ornamental design for a stethoscope name tag, as shown and described.

DESCRIPTION

FIG. 1 is a top perspective view of a stethoscope name tag showing my new design, with the broken line showing for illustrative purposes only and forming no part of the claimed design;

FIG. 2 is a side perspective view thereof, with the top portion shown in open condition;

FIG. 3 is a bottom plan view thereof, the top being a mirror image thereof;

FIG. 4 is a front elevation view thereof;

FIG. 5 is a rear elevation view thereof;

FIG. 6 is a right side elevation view thereof; and,

FIG. 7 is a left side elevation view from the side opposite the side shown in FIG. 6.
